UNITED STATES PATENT OFFICE

160,464

FRAME FOR AN AUTOMOBILE LAMP LENS

Harry T. Bannister, Huntington Woods, Mich., assignor to Chrysler Corporation, Highland Park, Mich., a corporation of Delaware

Application August 18, 1949, Serial No. 4,578

Term of patent 7 years

(Cl. D14—6)

To all whom it may concern:

Be it known that I, Harry T. Bannister, a citizen of the United States, residing in the city of Huntington Woods, county of Oakland, and State of Michigan, have invented a new, original, and ornamental Design for a Frame for an Automobile Lamp Lens, of which the following is a specification, reference being had to the accompanying drawing, forming part thereof, in which:

Fig. 1 is a perspective view of a frame for an automobile lamp lens showing my new design, the dotted line showing of a portion of an automobile being for illustrative purposes only.

Fig. 2 is a front elevation of the frame;

Fig. 3 is a top plan view thereof;

Fig. 4 is a side elevation of the frame; and

Figs. 5 and 6 are sections taken on the lines 5—5 and 6—6 respectively of Fig. 2.

I claim:

The ornamental design for a frame for an automobile lamp lens, substantially as shown and described.

HARRY T. BANNISTER.
